UNITED STATES PATENT OFFICE

2,580,102

LIQUEFIED FUEL VAPORIZER

Sam P. Jones, Dallas, Tex.

Application January 14, 1946, Serial No. 641,106

4 Claims. (Cl. 62—1)

1

The present invention relates to a vaporizer, and particularly a vaporizer for use with automotive equipment using volatile gas, such as liquid butane or propane, for fuel.

The present invention is related to applicant's prior patents, Nos. 2,252,261, August 12, 1941, and 2,255,747, September 16, 1941, and application Serial No. 630,786, filed November 26, 1945, now Patent No. 2,558,051, June 26, 1951, and has for its particular object the provision of a vaporizing system incorporated with a precipitation means to precipitate non-volatile, extraneous matter from the fuel.

A further object of the invention is to incorporate this precipitation chamber with the vaporizer unit. More particularly, it is an object of the invention to incorporate a precipitation chamber with a vaporizer column of the backflow type, in which the precipitation of the non-volatile matter may take place without interfering with the back flow of the liquid fuel from the vaporizer to the supply tank.

It is a specific object of the invention to provide a vaporizer unit of the foregoing backflow type, having a precipitation chamber associated with the vaporizer unit but separated from the vaporizing means in such wise that the back flow may occur in normal fashion, but in which the precipitation also may take place.

A further object of the invention is to provide a backflow vaporizer system wherein the exhaust gases of a motor operated by the generated gas are caused to act as the heating means for vaporizing additional gas from the liquid fuel.

In the drawings:

Fig. 1 is an elevation partly in section, showing the present mechanism;

Fig. 2 is an end elevation, taken from the right of Fig. 1; and

Fig. 3 is an enlarged transverse section of the 40 vaporizer unit, with the precipitation means thereon.

In general, the apparatus is used with a fuel tank 10 adapted to contain the liquid fuel from which the gas is generated. It includes also a 45 vaporizer unit, generally indicated at 11.

The vaporizer unit follows the form generally disclosed in the prior patents and application above referred to. It has a standpipe having a vaporizing chamber 12, above which is a pipe 13, and below which, in the present embodiment, is a precipitation chamber 14. A liquid fuel inlet pipe 15 is connected from the bottom of the supply tank 10. The pipe 15 enters the vaporizing chamber 12 and has its inner end 16 down-

2

turned and ending at a downward point that may be considered the bottom of the vaporizing chamber 12, as distinguished from the precipitation chamber 14. As shown in the prior patents, suitable valve control for the inlet of fuel through the line 15 may be provided, as desired.

The upper end of the pipe 13 is connected by a T 20 with an outlet line. This line contains a valve 21, a pressure regulator 22, and a final discharge pipe 23, this last leading to the engine or other mechanism to be operated by the gas.

The upper end of the tube 13 is also connected to the top of the tank 10 through the T 20. To this end, there is a pipe connection 25, in which are interposed a conventional excess flow valve 26 and a combination check and back-feed valve 27. The check valve opens when the vapor pressure at the top of the tank 10 exceeds the vapor pressure in the standpipe 13 by a predetermined amount, in the manner disclosed in the patents. The combination valve 27 also opens to permit back flow of vapor from the vaporizing chamber 11 to the tank 10 when the vapor pressure in the tank 10 reaches a predetermined minimum. 25 This combination valve or its equivalent is disclosed in the prior patents in forms adequate for the present purposes.

The vaporizing chamber 12 has heat conducting walls that are surrounded by a housing 30 that receives exhaust gases from the gas engine by a pipe 31. Opposite the exhaust pipe 31, the housing 30 is provided with louvers 32, from which the exhaust gases may escape. The pipe forming the chamber 12 has a plurality of heat catching fins 33 therearound, formed as flanged rings. The number employed is suitable to the size of the housing 30. The arrangement is such that the exhaust gases will circulate around the pipe 12 in the area indicated, delivering heat to the pipe, this delivery being enhanced by the presence of the fins 33. It will be seen that the housing 30 is disposed above the inlet pipe 15.

Below the outlet 16 of the inlet pipe 15 is the precipitation chamber 14. This chamber is provided with a drain cock 36 which may be opened from time to time to remove the precipitates.

Operation

In general, the operation of this mechanism is 50 the same as that in the prior patents and application of this inventor. Liquid fuel from the tank 10 flows through the inlet pipe 15 and out its discharge opening 16 to rise in the standpipe of the vaporizer chamber until it attains the level 55 of the liquid in the tank 10. At all normal tem-

peratures, there will be a certain amount of vapor above the liquid in the tank 10 and in the vaporizer 11.

Assuming that this mechanism is used with a gas engine, the vapor will be supplied to the outlet line 23 through the manual valve 21 and the pressure regulator 22. When the gas engine is started, it will draw off immediately the vapor at the top of the standpipe 13. Usually this amount of vapor is insufficient to operate the gas engine for any period of time; and, as will appear, the heat generation of additional vapor is dependent upon the delivery of hot exhaust gases from the engine to the housing 30. As a result, the preliminary operation of the engine will normally produce a low pressure condition in the standpipe 13 at the start, which low pressure is lower than the vapor pressure above the liquid in the tank 10. When this pressure differential attains a value that is predetermined, the check valve 27 will open to permit the vapor above the liquid in the tank 10 to be drawn through the pipe 25 and be delivered to the gas engine to supplement the fuel already supplied from the standpipe and to continue the operation of the engine, despite the deficiency in gas supplied from the standpipe. This latter amount of vapor is sufficient to operate the engine for a period of time long enough that the engine exhaust gases will heat the vaporizer chamber 12 and cause the generation of more vapor therein. When this heating by exhaust gases is well established, the vaporizer unit 11 will supply all of the fuel requirements of the engine. As the pressure in the vaporizer unit is restored by this generation, the check valve 27 will close, thus stopping the withdrawal of vapor from the top of the tank 10.

As noted in the prior patents and application, the vapor pressure above the tank 10 must not be held at a low value with particular respect to the temperatures of the liquid. To avoid this, the feed-back feature of the combination valve 27 is provided, and, as set forth in the prior inventions disclosed, this valve will cause vapor to flow from the vaporizer chamber into the top of the tank 10 to maintain a predetermined minimum vapor pressure in the tank.

If the amount of vapor generated by the vaporizer 11 is greater than that required by the gas engine, the pressure within the vaporizer chamber will increase above the pressure in the tank 10. This increase of vapor pressure, even though slight, will then depress the liquid level in the vaporizer chamber. As already noted, the outlet 18 of the inlet pipe 15 is disposed below the effective heating area of the housing 13 on the chamber portion 12, and the liquid level may be depressed by the aforementioned excess pressure to drive the liquid from the vaporizer 11 back through the pipe 15 into the tank 10. This will reduce the level of liquid within the vaporizer to a point below the heated area of the vaporizer chamber, and thereby will substantially eliminate vaporization, if the requirement of the gas engine is lowered to a minimum or is stopped entirely. Thus the liquid level in the vaporizing chamber will adjust itself automatically to suit the demand of the gas engine.

In systems of the present kind, the precipitates have introduced serious problems because they interfere with the operation of the vaporizer mechanism and with the operated device, such as the carburetor of the gas engine already mentioned. These precipitates are eliminated in the

present invention before they can get to any point in the vaporizing unit or carburetor, where their presence would cause trouble. The liquid fuel coming in through the pipe 15 is discharged downwardly into the precipitating chamber 14 and establishes a level that is never lower than that indicated in Fig. 3, even with a depressed liquid level, caused by excessive generation of vapor beyond the requirement. As the precipitation chamber 14 is, for all practical purposes, outside of the heated zone, there will be substantially no evaporation occurring from the amount of liquid shown in Fig. 3. However, all of the functions of the backflow system are preserved in this arrangement. It also provides a chamber in which the heavy particles may precipitate out and ultimately be removed when they have accumulated. Such removal is conveniently made by opening the drain cock 36.

In other words, the present invention provides for the precipitation of the extraneous materials without interfering with the backflow system, whereby liquid is always free to return from the vaporizer to the storage tank whenever the rate of vaporization exceeds the rate of demand. All this is accomplished by introducing the liquid into the vaporizer at the bottom of the heating zone and by providing, below that zone, a precipitation chamber. Any extraneous material that might possibly succeed in reaching the vaporizer column 12 also will tend to precipitate to the bottom thereof.

What is claimed is:

1. In a vaporizer mechanism of the backflow type, a chamber adapted to contain liquid in its lower parts and vapor above the liquid, heating means to supply heat to the chamber to vaporize liquid therein, said means being arranged to heat the chamber in substantial degree only above a given level, a liquid inlet into the chamber comprising a tube having its end turned downwardly and opening at said level, whereby liquid therebelow will not be substantially vaporized by the heating means.

2. In a vaporizer mechanism of the backflow type, a vaporizer unit comprising a vertical tubular column, an inlet pipe at the lower end of the column for connection with a liquid supply tank, an outlet pipe means at the upper end having a pipe for connection with the top of the tank and having a pipe for connection with an outlet line leading to a gas engine, a heating housing around the column at its lower end for connection with the exhaust of the gas engine, and valve means in the outlet pipe for connection with the top of the tank said valve means being pressure-responsive to open said pipe when the gas pressure in the tank exceeds that in the column by a predetermined amount.

3. In a vaporizer mechanism of the backflow type, a vaporizer unit comprising a vertical tubular column, an inlet pipe at the lower end of the column for connection with a liquid supply tank, an outlet pipe means at the upper end having a pipe for connection with the top of the tank and a pipe for connection with an outlet line leading to a gas engine, a heating housing around the column at its lower end for connection with the exhaust of the gas engine, valve means in the outlet pipe leading to the tank, for connection with the top of the tank and the outlet line, said valve means being pressure-responsive, to open the pipe when the gas pressure in the tank exceeds that in the column by a predetermined amount, said housing being disposed above the

bottom of the column, the inlet being below the housing, and a precipitation chamber in the column below the inlet.

4. In a vaporizer mechanism of the backflow type wherein a vaporizer chamber is adapted to be connected to a reservoir of vaporizable liquid to receive liquid therefrom under pressure head of a predetermined range and to deliver vaporized liquid to a load of varying rate of consumption: an upright vaporizer chamber adapted to contain the vaporizable liquid as aforesaid in its lower parts and vapor above the liquid; an inlet into the chamber for admitting the liquid thereto, the inlet comprising connections adapted to be connected with the liquid reservoir so as to dispose the chamber alongside the reservoir so that liquid from the reservoir will normally initially rise at least to a predetermined level above the bottom of the chamber, the inlet having its opening into the chamber below said liquid level, but above the bottom of the chamber to provide a well below that opening; an outlet for vapor at the upper end of the chamber; a pressure regulator connected with the outlet to limit the line pressure from the regulator; heating means positioned next to the chamber to provide heat in substantial degree only in a zone of the chamber above the inlet opening; the heating means

being adapted to heat the liquid in said zone of the chamber and to develop a vapor pressure in the chamber, the heating means being of a capacity to produce a vapor at a rate greater than that admitted through the pressure regulator and sufficient to depress the liquid level from the heating zone back through the inlet opening when the rate of vaporization produces vapor at rates greater than that admitted through the regulator; the well below the inlet opening being outside the heating zone whereby it may fill with liquid to the level of the inlet opening without thereby causing substantial generation of vapor.
